UNITED STATES PATENT OFFICE.

CLARENCE E. LOMAX, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed June 25, 1923. Serial No. 647,425.

To all whom it may concern:

Be it known that I, CLARENCE E. LOMAX, a citizen of the United States of America, and a resident of Chicago, Cook County, 55 and State of Illinois, have invented certain new and useful Improvements in Automatic Telephone Systems, of which the following is a specification.

This invention relates in general to automatic telephone systems and its object, broadly stated, is to provide a new and improved arrangement of trunking by using plunger (Keith) type primary line switches, and secondary finder switches associated 15 with first selectors.

The above pointed out object, together with others not specifically mentioned at this time, will be pointed out and explained more fully hereinafter, reference being had to 20 the accompanying drawings comprising Figs. 1 and 2, of which Fig. 1 is a schematic diagram of the trunking arrangement, while Fig. 2 shows circuit diagrams of the equipment in use.

25 Referring now particularly to Fig. 1, the trunking arrangement will first be briefly explained, as this will render it easier to understand the circuits. This diagrammatic layout shows in simple form the 30 trunking between local subscriber lines A and first selectors E in an automatic exchange. For example, 100 subscriber lines A, terminating in plunger type primary line switches C, have access to ten outgoing 35 trunks, the selection of an idle trunk being controlled by the master switch D. The ten outgoing trunks terminate in secondary 40 finder switch banks, and when a trunk is seized it is located by an idle secondary 45 finder switch F and connected to the associated first selector switch E. Since the bank of a finder switch, as indicated in this case, is a thirty point bank, it is obvious that three such groups as explained 50 above can be accommodated. The finder switch bank contacts are multiplied so that each primary trunk is accessible to each finder switch, there being twenty-five of the latter in this case, as indicated. A start 55 wire extends from each of the master switches to a common distributor O, the lat-

ter operating to stand opposite an idle finder and selector, and permitting said wire to start the finder hunting for the seized trunk as already mentioned.

Having explained the trunking arrangement adopted, the apparatus shown in the circuit diagrams may now be briefly described. The substation A, Fig. 2, is an ordinary automatic telephone substation 60 having the usual talking instrumentalities and a calling device for controlling the automatic switches. The line conductors terminate at the exchange in the individual line switch C, which is of the well known 65 plunger type, modified however, in circuit arrangement, to be hereinafter explained in detail in connection with its operation.

The master switch D is of the type shown 70 and described in the U. S. Patent to Newforth, No. 13,901, reissued April 13, 1915, modified however, to include supervisory relays and associated signal and start wire circuits.

The distributor O is a non-numerical 75 switch mechanically of the well known rotary type in which the wipers have no normal position and move in a forward direction only. Its function is to stand opposite an idle finder, such as F, and connect 80 the start wire thereto. Its stepping magnet is operated by a seized selector, such as E, and it must contain at least as many contact points as there are pairs of selectors and finders in the group.

The secondary finder switch F is also a 85 non-numerical switch mechanically of the well known rotary type in which the wipers have no normal position and move in a forward direction only. Its function is to 90 hunt for a trunk seized by a primary line switch and, when found, operate to connect same through to the selector E, and disconnect the hunting mechanism.

The first selector E, shown only in part, is 95 mechanically of the usual and well known Strowger vertical and rotary type, modified however, in circuit arrangement to send back ground potential, separate from the release trunk ground potential, from the release relay to the stepping magnet of the 100 distributor O.

Having briefly explained the purpose of the invention and the apparatus involved in carrying it out, the operation of the equipment may now be explained more in detail. For this purpose it will be assumed that the subscriber at substation A desires to obtain connection with a subscriber (not shown) accessible by way of the first selector E.

When the calling subscriber at substation A removes his receiver to initiate the call, an energizing circuit is completed over the line conductors 11 and 12 for the line relay 14 of the line switch C. Upon energizing, line relay 14 closes a locking circuit at armature 21 for itself in series with the pull-in winding 18, by way of ground at relay 30 and said relay, armature 21 and its working contact, lower winding of relay 14, winding 18, resting contact of armature 31 and said armature, and grounded battery; closes a circuit at armature 20 for the hold winding 17, which is in multiple with winding 18, and places ground potential, by way of conductor 13, on the multiple test contacts in the banks of connector switches having access to the line of substation A, whereby said line is made busy. Pull-in winding 18, upon energizing, operates both the plunger arm 15 and the cut-off armature 16; the former, through the medium of its plunger (not shown) forces the bank springs 40-43, inclusive, into engagement, respectively, with the contacts 44-47, inclusive, and the latter disconnects the line conductors 11 and 12 from the line relay 14 and from ground, respectively. By the engagement of bank springs 40-43, inclusive, with contacts 44-47, inclusive, the line, test, and holding conductors are extended to bank contacts 50-53, inclusive, of the finder switch F.

By the extension of the test conductor at spring 42 and contact 46, ground potential is placed on test contact 52 and its multiples in the banks of the finders. It may be pointed out in this connection that the lower winding of relay 14 and the winding of relay 30 are of very low resistance, preferably not over a couple of ohms each, so that test contact 52 is brought substantially to ground potential, as stated.

By the extension of the holding conductor, at bank spring 41 and contact 45 a circuit is closed from ground, relay 30, armature 21 and its working contact, lower winding of relay 14, working contact of armature 20 and said armature to the master switch D, whereby said switch is operated in the well known manner to advance the plungers of all the remaining idle line switches into position before the terminals of the next idle trunk line. During the operation of the master switch the branch circuit including the pull-in winding 18, is

open at armature 31, but the other branch circuit including the holding winding 17, is sufficient to hold relay 14 energized, and plunger arm 15 in operated position.

Relay 30, upon energizing, closes a circuit 70 at armature 34 for slow acting relay 32. Relay 32, upon energizing, connects ground to start wire 36 at armature 35; and closes a circuit at armature 33, whereby a lamp L is lighted, and an audible alarm (not shown) 75 is operated whenever this relay is held up for more than a predetermined number of seconds.

If finder switch F wipers 54-57, inclusive, happen to be standing on the trunk contacts 50-53, inclusive, when the line switch C plunges and seizes this trunk, as shown, a circuit may be traced as follows: Grounded test contact 52, wiper 56, lower winding of relay 65, grounded battery. Relay 65, upon energizing, opens the circuit of the motor magnet 58 at armature 62, thus preventing rotation of the switch. If finder switch F wipers 54-57, inclusive, are not standing on the trunk seized by the line switch C, a circuit may be traced as follows: Grounded start wire 36, wiper 73, contact 75, resting contact of armature 62 and said armature, resting contact of armature 59 and said armature, motor magnet 58, and grounded 90 battery. Magnet 58 energizes and deenergizes over this circuit, thus operating to rotate the wipers 54-57, inclusive, into engagement with the seized trunk contacts, which in this case are 50-53, inclusive. 100 When the wipers reach the contacts, a circuit is closed for relay 65 by the engagement of test wiper 56 with grounded test contact 52, which relay, upon energizing, opens the circuit of the motor magnet 58, and closes 105 the circuits of the line, holding and guard wire conductors through to selector E.

The line relay 80 of selector E now becomes energized over the circuit from ground, working contact of armature 19 and said armature, spring 40, contact 44, contact 50, wiper 54, armature 60 and its working contact, armature 84 and its resting contact, upper winding of relay 80, to grounded battery; whereupon the release relay 81 energizes to connect ground to the release trunk conductor and guard conductor at armatures 82 and 83, respectively. The ground placed on the negative conductor 12 at armature 19 thus forms a holding circuit 110 for relay 80 and helps to prevent preliminary impulses caused by accidental or other operations of the subscribers switchhook preliminary to the dialling of the desired number. The following circuit may now be traced: Ground, armature 82 and its working contact, working contact of armature 61 and said armature, wiper 55, contact 51, contact 45, spring 41, armature 20 and its working contact, winding 18, resting con- 115

tact of armature 31 and said armature, to grounded battery. Relay 65 and winding 17 are held energized in multiple over this circuit and the make busy condition, previously described, is transferred to it. Relays 14 and 30 are shunted out and the former relay, upon deenergizing, removes ground from negative line conductor 12 at armature 19; opens the original holding circuit at armature 20; and opens the circuit to relay 30 at armature 21. Relay 30, upon deenergizing, removes ground from start conductor 36. Relay 32, upon deenergizing, opens the alarm circuit, containing lamp L, at armature 33.

At the same time that relays 14 and 30 are shunted, a circuit may be traced from ground, working contact of armature 83 and said armature, working contact of armature 63 and said armature, contact 74, wiper 72, resting contact of armature 71 and said armature, motor magnet 70, to grounded battery. Magnet 70 now energizes and deenergizes to rotate the wipers 72 and 73 into engagement with contacts leading to the first idle finder and selector switch combination. The selected idle finder is not started because ground has already been removed from the start wire 36 by the falling back of relay 30.

The calling subscriber may now operate his calling device in accordance with the first digit of the called number, and the selector E will raise its wipers to the correct level and rotate in to select an idle trunk leading to a succeeding switch, whereupon its switching relay will operate to extend the connection. Ground potential is returned from the last seized switch, up to and including the connector, over the holding conductor to hold up the preceding switches; all of which is in the usual and well known manner.

The calling subscriber will finally terminate the conversation, and will replace his receiver, bringing about the disconnection of the apparatus in the usual manner. Briefly, upon the deenergization of the line relay of the connector (not shown), its release relay deenergizes and breaks the holding circuit of the preceding switches, whereby all the switches including the selector E, finder switch F and line switch C are restored to normal position.

This same arrangement can obviously be used for other combinations of subscribers' lines, outgoing primary trunks, and finder and selector switches, depending upon the traffic conditions; and can also be extended to any desired size of finder and distributor switch banks without departing from the spirit of the invention. Furthermore, Strowger vertical and rotary type switches may be used as secondary finder switches if so desired.

The advantage in the use of plunger type primary switches with rotary type finder secondary switches is that it increases the size and efficiency of the selector groups over those that could be obtained by using the straight plunger type primary switches alone, and accomplishes this object without using the relatively expensive rotary switches as individual switches, and without using secondary line switches, which require complicated multiplying of the primary trunks in the secondary groups and complicated group busying arrangements, etc.

Having described my invention, what I consider to be new and desire to have protected by Letters Patent will be pointed out in the appended claims.

What I claim is:

1. In a telephone trunking system, a plurality of groups of individual line switches, groups of trunk lines accessible to said groups of line switches, there being one group of trunk lines for each group of line switches, a group of first selecting switches comprising a greater number of switches than there are trunk lines in any of said groups, the number of switches being, however, less than the total number of such trunk lines, finder switches inserted in the system between the said trunk lines and first selectors, each finder being directly connected to a particular first selector and having access to all of said trunk lines, means for operating a line switch and a finder switch to connect a calling subscriber's line with an idle first selector, and means in such selector controlled over the calling line for maintaining the operated line and finder switches in operated position.

2. In a telephone trunking system, a plurality of preselecting individual line switches, a group of non-preselecting finder switches, trunk lines connecting the banks of said line switches with the banks of said finder switches, a first selector switch individual to and directly connected with each finder switch, subscribers' lines terminating in said line switches, means responsive to a call for operating a line switch and a finder switch in quick succession to connect the calling line with an idle first selector, and means for operating such selector responsive to impulses transmitted from the calling station.

3. In a telephone trunking system, a plurality of groups of preselecting individual line switches, a single group of non-preselecting finder switches, trunk lines connecting the banks of said line switches with the banks of said finder switches, a first selector switch individual to and directly connected with each finder switch, and a distributor switch controlled by said selector switches for preselecting idle finder switches.

4. In a telephone trunking system, a plu-

rality of groups of preselecting individual line switches, a single group of non-preselecting finder switches, trunk lines connecting the banks of said line switches with the 5 banks of said finder switches, a first selector switch individual to and directly connected with each finder switch, means associated with each group of line switches responsive to the operation of a line switch in the group 10 for controlling the starting of a finder switch, a distributor switch by means of which the control is exercised, and circuit arrangements controlled by the selector switches for maintaining said distributor switch in readiness to start an idle finder.

5. In a telephone system, subscribers' lines, line switches individual to said lines, trunk lines accessible to said switches, first selectors, finder switches individual to said 20 first selectors, respectively, for connecting the same with said trunk lines, means controlled over a subscriber's line responsive to the initiation of a call thereon for automatically operating the line switch individual to 25 such line and the finder switch associated with an idle selector to extend such calling line over one of said trunk lines to such idle first selector, and means for then operating said first selector under the directive control of the calling subscriber to extend the 30 calling line in the direction of the called line.

6. In a telephone system, a subscriber's line, a selector switch, means responsive to 35 the initiation of a call thereon for extending said line to said selector, said means including a line switch individual to said line, and a finder switch individual to said selector, a release trunk conductor extending through 40 said finder switch from the line switch to the selector, cut-off and switching relays in said line and finder switches, respectively, connected to said conductor, and means in said selector for connecting a source of current to said conductor to energize said relays.

7. In a telephone system, means including 45 a line switch and a finder switch in serial relation and operable successively for extending a line to a trunk line, a line relay in said line switch and means for disconnecting the same from the line when the line switch is operated, and a locking circuit for holding said line relay energized while said finder is operating.

8. In a telephone system, means including 50 serially related line and finder switches for extending a line to a trunk line, means responsive to a call on said line for initiating the operation of said switches, means for locking said line switch in operated position independent of control over the calling line while the finder switch is operating, and means automatically responsive to the completion of the operation of the finder for

again placing said line switch under control 65 of the calling line.

9. In a telephone system, a line, a switch individual to said line, trunk lines accessible to said switch at one end, a finder switch having access to said trunk lines at the other 70 end, means responsive to a call on said line for operating said line switch to connect with an idle trunk line and for starting said finder in search of such trunk line, said means including a line relay in said line 75 switch, means for disconnecting said line relay when the line switch is operated, and a locking circuit for holding said line relay energized until after the finder switch has found the trunk line.

10. In a telephone system, a line, a switch individual to said line, trunk lines accessible to said switch at one end, a finder switch having access to said trunk lines at the other end, means responsive to a call on said line 80 for operating said line switch to connect with an idle trunk line and for starting said finder in search of such trunk line, said means including a line relay in said line switch disconnected when the switch is operated, a holding circuit for said switches including a conductor of the connected trunk line, a locking circuit for said line relay effective to supply current to said holding conductor while the finder is operating, and 85 means effective after the finder has found the connected trunk line for supplying current to said conductor from another point, whereupon said line relay is deenergized.

11. In a line switch having movable contacts for connecting the conductors of a calling line, with the conductors of an idle trunk line, a controlling line relay, and contacts on said line relay for directly grounding one of said movable contacts.

12. In a line switch having access to a group of trunk lines, means including a line relay for operating the switch to connect with an idle one of said trunk lines, and contacts on said line relay for grounding a talking conductor of the connected trunk line.

13. In a telephone system, trunk lines, line switches having access to said trunk lines at one end, finder switches having access to said trunk lines at the other end, each of said finder switches having its wipers normally in engagement with some one of said trunk lines, means for operating a line switch to seize an idle trunk line, means for starting an idle finder, and means for preventing movement of the finder in question in case the wipers thereof are in engagement with the seized trunk line.

14. In a telephone system, trunk lines, line switches having access to said trunk lines at one end, finder switches having access to said trunk lines at the other end, each of said finder switches having its wipers

normally in engagement with some one of said trunk lines, an automatic switch individual to each finder switch, means for operating a line switch to seize an idle trunk line, means for causing an idle finder switch to hunt for the seized trunk line in order to extend the same to the associated automatic switch, and means in the finder in question

for at once extending the seized trunk to such automatic switch in case the finder switch wipers happen to be already in engagement with the seized trunk line.

In witness whereof, I hereunto subscribe my name this 21st day of June, A. D., 1923.

CLARENCE E. LOMAX.
